CLAIM

The ornamental design for a medical diagnostic equipment, as shown and described.

DESCRIPTION

FIG. 1 is a front-left perspective view of a medical diagnostic equipment according to a first embodiment of the claimed design.

FIG. 2 is a rear-right perspective view of the medical diagnostic equipment of FIG. 1.

FIG. 3 is a front view of the medical diagnostic equipment of FIG. 1.

FIG. 4 is a rear view of the medical diagnostic equipment of FIG. 1.

FIG. 5 is a left side view of the medical diagnostic equipment of FIG. 1.

FIG. 6 is a right side view of the medical diagnostic equipment of FIG. 1.

FIG. 7 is a top view of the medical diagnostic equipment of FIG. 1.

FIG. 8 is a bottom view of the medical diagnostic equipment of FIG. 1.

FIG. 9 is a front-left perspective view of a medical diagnostic equipment according to a second embodiment of the claimed design.

FIG. 10 is a rear-right perspective view of the medical diagnostic equipment of FIG. 9.

FIG. 11 is a front view of the medical diagnostic equipment of FIG. 9.

FIG. 12 is a rear view of the medical diagnostic equipment of FIG. 9.

FIG. 13 is a left side view of the medical diagnostic equipment of FIG. 9.

FIG. 14 is a right side view of the medical diagnostic equipment of FIG. 9.

FIG. 15 is a top view of the medical diagnostic equipment of FIG. 9; and,

FIG. 16 is a bottom view of the medical diagnostic equipment of FIG. 9.

The broken lines illustrate portions of the medical diagnostic equipment that form no part of the claimed design; the broken lines form no part of the claimed design.

In the drawings, the stippled shading represents surfaces having the contrast in appearance shown.
